Atty.

UNITED STATES PATENT OFFICE

GEORGE HAMILTON-GRAPES, OF MURRUMBEENA, VICTORIA, AUSTRALIA

CARBURATION OF HYDROCARBON FUEL FOR INTERNAL-COMBUSTION ENGINES

Application filed July 27, 1927, Serial No. 208,786, and in Great Britain August 5, 1926.

The present invention refers to the carburation of hydro-carbon fuel for internal combustion engines and specifically to the system in which the heavy moist particles in a carburetted mixture stream are deflected out of the mixture during the passage of said particles from the carburetting device to the engine cylinders.

The beforementioned system is the subject of applicant's United States Patent No. 1,471,599 and certain improvements therein are the subject matter of applicant's pending application, Serial No. 93,999. In said patent the conductor proceeds in a circuitous form and in the application in substantially an S-twist or double curve from the carburetter to a retort chamber. The downwardly directed curved portion of said conductor is in superposed relationship to the mouth of a receiving chamber and deflecting means are provided in the conductor to divert moist particles into said mouth.

It has been found by experimental investigation that during cold starting periods or slow running of the engine and particularly when using fuel having a high distillation point that non-vaporized particles in the conductor beforementioned which for convenience is termed the separator element, accumulate in considerable quantity and gravitate into the receiving chamber which is then in a low temperature condition.

To obviate this disability is the purpose of the present invention.

Broadly stated the invention consists essentially of means provided in the separator element at or in close proximity to the downwardly directed portion of same for deflecting the moist particles into the receiving chamber located outside the active sphere of the mixture stream. Said receiving chamber may be connected to a reserve tank or alternatively may feed said particles into a retort chamber, the feed being controlled by metering pin.

The accompanying drawings illustrate a practical application of my invention for the purpose stated.

In these drawings:

Figure 1 is an end partial sectional view of the separator element,

Figure 2 is a partial sectional elevation.

Figure 3 is a plan, and

Figure 4 is a section on line 4—4 in Fig. 2.

Referring now to the drawings it will be noted that the flange 8 is utilized with the horizontal offset portion 9 to form the base of a truncated conically shaped receiving chamber 10 which communicates with a sinuous or S-shaped separator element A by means of the aperture or slot 11 formed in the underneath side of the latter at a position slightly below the level of the peak of a deflector 12 on the upper wall of said element A where the element makes a reverse bend. The element A preferably increases in cross section. The slot 11 preferably describes an arc equivalent to about three-quarters of the circumference of the separator element at the position where the slot is provided, and there is an antecedent lip 17.

The function of the antecedent lip 17 and slot 11 is to trap, at periods of starting up from cold during idling, and slow running operations of the engine, the higher-boiling liquid fuel fractions and convey same to the receiving chamber 10.

By these means flooding by the irregular use of the air choker fitting of the carburetter is prevented as well as the passage of froth into the main mixture stream, by the sudden addition of a large volume of fuel and fuel vapor, formed and released as soon as an appreciable temperature is reached in the running engine.

Normally about 70 c. c. would be separated out of the fuel mixture stream before a start is made in cold weather but should the capacity of the receiving chamber be 200 c. c. and it be filled with heavy fuel-fractions before an engine start is effected, the whole of this amount may be subsequently slowly fed into a retort chamber 16 through a metering jet or orifice 13 provided in the flange 8 which is coupled to the flange 8^a of said retort chamber. The heavy fuel may thus be slowly introduced to the retort chamber over an appreciable time period. The length of this period is governed by the regulating

screw 14 which adjusts the amount of flow of fuel per minute so as to efficiently harmonize with engine requirements.

There is an opening 19 in the bottom of the separator element A that discharges through the opening 20 into the top of the separator chamber 16 and this opening is separated from the receiving chamber by a wall 21, Fig. 4. The receiving chamber is provided with a cleanout opening closed by nut 18.

Should, however, more than 200 c. c. of fuel be collected at starting an engine, the excess passes away through overflow pipe 15

of appreciable dimensions which may con-

duct same to a fuel tank such as a reserve tank located under the dash-board of a motor vehicle.

If for any reason it be deemed expedient to totally prevent the entry of any heavy or higher boiling fuel fractions into the retort during starting the feed regulator screw 14 may be closed. Such action would divert the whole of these fuel fractions into the reserve fuel supply tank through the connection 15. Such tank may be used entirely for emergency purposes or its contents may be returned to the main fuel or service supply tank of a motor vehicle.

The slot 11 is so designed and arranged that it will only trap the unvaporized liquid fuel fractions when the inertia moment of the fractions is of a low order, as when the "starter" is operated. At high speeds the

velocity of the wet mixture pulls this mixture

past the lip 17 and slot 11 and through the inertia and centrifugal force drops the heavy liquid particles through openings 19, 20 into the retort 16. The deflector 12 diverts liquid

element and means to deliver collected liquid in the receiving chamber to the retort chamber.

2. Means for extracting liquid particles from a carburetted fuel mixture, comprising a sinuous separator element for insertion between a carburetter and an internal combustion engine, and having a slot in a downwardly directed lower portion thereof, a deflector preceding said slot and on said portion and on the opposite wall thereof to direct liquid following the upper wall toward the slot; a receiving chamber into which said slot discharges, a retort chamber connected to the bottom of said element, and

of appreciable dimensions which may conduct same to a fuel tank such as a reserve tank located under the dash-board of a motor vehicle.

said slot discharges, a retort chamber connected to the bottom of said element, and means to deliver liquid collected in said chamber into the retort chamber.

3. Means for extracting liquid particles from a carburetted fuel mixture, comprising a sinuous separator element having a slot in a portion inclined toward the bottom thereof, and an opening in its bottom, a receiving chamber into which said slot discharges, a retort chamber connected to said opening and a regulable orifice connecting the retort chamber and receiving chamber for delivery of liquid collected in the receiving chamber to the retort chamber, there to be vaporized and the vapor returned to the element.

4. Means for separating liquid particles from a carburetted fuel mixture, comprising a sinuous separator element having a slot in the lower wall of its portion directed to the bottom of the element, a deflector on the upper wall of the element anteceding the slot,

a receiving chamber into which said slot delivers liquid, and an overflow pipe for the receiving chamber below the level of the slot.

5. Means for separating liquid particles from a carburetted fuel mixture, comprising

of appreciable dimensions which may conduct same to a fuel tank such as a reserve tank located under the dash-board of a motor vehicle.
